UNITED STATES PATENT OFFICE.

HERMAN C. NICHOLAUS, OF DETROIT, MICHIGAN, ASSIGNOR OF ONE-HALF TO FRANK H. RATEICK AND ONE-HALF TO WILLIAM J. LOOMAN, BOTH OF DETROIT, MICHIGAN.

TIMING MECHANISM.

1,107,176.

Specification of Letters Patent. Patented Aug. 11, 1914.

Application filed September 7, 1912. Serial No. 719,173.

To all whom it may concern:

Be it known that I, HERMAN C. NICHOLAUS, a citizen of the United States of America, residing at Detroit, in the county 5 of Wayne and State of Michigan, have invented certain new and useful Improvements in Timing Mechanism, of which the following is a specification, reference being had therein to the accompanying drawings.

10 This invention relates to a timing mechanism for an electric switch whereby the latter may be thrown in at any desired time, held closed for a desired period and then automatically opened again.

15 The invention consists in the matters hereinafter set forth, and more particularly pointed out in the appended claims.

In the drawings, Figure 1 is a plan view, partially broken away, of mechanism that 20 embodies features of the invention showing the device set ready for throwing a switch shut. Fig. 2 is a similar view showing the position of the mechanism with the switch closed; Fig. 3 is a similar view of the mechanism showing the parts as they are returning to initial position; and Fig. 4 is a view in detail in section showing the disposition of index and dial plates.

In general terms the mechanism includes 30 a master clock mechanism which may be set to run for any desired length of time and which may be of any desired type, a cam operating mechanism controlled by the time or clock movement and a switch having throw-in and cut-out members controlled by the cam operating mechanism.

As herein shown in preferred form a base 1 supports a clock mechanism indicated at 2 of any preferred type with the hour hand 40 arbor 3 carrying a dial 4 which rotates a detent plate 5 with a notch indicated at 6 in its periphery. A friction plate 7 has a sleeve 8 by which it is concentrically journaled on the barrel of the plate 4 with a 45 plurality of spring fingers 9 engaging a time plate 10 that is divided into hour spaces similar to a clock face. A thumb latch 11 enables the plates 4 and 10 to be set in any desired relation as the latter has notches engaged by the latch. A pointer 12 on the base forms the zero or starting point.

A rotatable cam 13 is driven by means of a pinion 14 in mesh with a gear 15 that is turned by a clock train movement or 55 other spring actuated mechanism that is

controlled or steadied by a fly 16 or the like. A detent lever 17 is pivoted in such manner that its upper end portion lies in the path of and arrests the fly when its lower arm 18 is thrown back by a lug 19 on a lever 20. An extremity 21 of the latter rides on the plate 8 that moves with a dial 10 and when such extremity drops into a notch 22 in the plate 8 it causes the member 17 to momentarily clear the fly 16 and allow 60 the cam 13 to rotate. This movement continues until an arresting member 24 has been thrown by a pin 43 on the cam against the heel 26 of the lever 20 so that the finger 19 is retracted as the latter is lifted from 65 the notch 22. This results in the return by a suitably disposed spring 27 of the lever 17 to arrest the fly 16 as indicated in Fig. 2.

A lever 28 oppositely disposed to the 75 member 20 has an inturned extremity 29 that rides on the plate 5 moving with the dial 4 so that when it drops into the notch 6 as the latter moves forward under the influence of the time mechanism, its upper 80 end portion 30, that hooks over the lever 17 retracts the latter and releases the fly 16 again as indicated in Fig. 3. This permits the cam 13 to make another revolution and in so doing an intermediate finger 31 85 on the lever 24 bears against the projection 32 on the lever 28 and thereby moves the upper portion 30 forward so that the lever 17 is again returned by the spring 27 to 90 intercept and hold the fly 16.

The first movement of the cam 13 from the initial position shown in Fig. 1 presses out a master lever 33 having a spring connection with a depending arm 34 of a switch lever 35 by means of a coil 36. At the same time a pin 43 pushes against an arm 47 of a latch bar 37 so that the latter is shifted sufficiently to disengage itself from a stop 38 on the lever 35 and allow the latter to drop into the hooked end 39 of the latch. As a consequence the spring 36 moves the lever 35 into the position indicated in Fig. 2 against the influence of a weaker spring 40 and thereby depresses and closes a switch arm 41 to which it is coupled by a link 42. 100 At this moment the fly 16 is arrested and the parts remain in the position shown in Fig. 2 until the timing mechanism through the lever 28 again releases the fly and permits the further rotation of the cam. As 110

the lever 32 drops over the point of the cam, it releases the tension on the spring 36 thereby allowing the spring 40 to return the lever 35, the parts assuming the position 5 shown in Fig. 3 toward the end of this movement and ultimately coming to rest in the position shown in Fig. 1.

As a result of this construction a switch 10 that is controlled by this mechanism and which itself may be of any preferred type 15 and form of construction, a damper or any regulating means may be opened or closed at the will of the person setting the mechanism at any hour and held in that condition 20 for a desired length of time. This makes the device of a special value for controlling switches to illuminating signs, show windows or other like places.

Obviously, changes in the details of construction 25 may be made without departing from the spirit of the invention and I do not care to limit myself to any particular form or arrangement of parts.

What I claim is:—

25 1. A timing mechanism comprising a master clock train having a detent plate and a dial plate in adjustable angular relation driven by the hour arbor of the train, switch throwing means, a clock train for operating 30 the switch throwing means, and means operated alternately by the detent and dial plates for momentarily releasing the operating train.

35 2. A timing mechanism comprising a master clock train, a detent plate and a dial plate angularly adjustable on the hour arbor of a train, switch throwing means, a clock train for operating the switch throwing means, and a member adapted to engage and 40 arrest the clock train and moved alternately by the detent and dial plate out of engagement with the train.

45 3. A timing mechanism comprising a master clock train, a detent plate and a dial plate angularly adjustable on the hour arbor of the train, oscillatory means for opening and closing a switch, a clock train adapted to oscillate the opening and closing means, and means normally engaging and arresting 50 the train that is operated alternately by the detent and dial plate to momentarily release the operating train.

55 4. A timing mechanism comprising a master clock train, a detent plate secured on the hour arbor thereof, a dial plate secured on the arbor in adjustably angular relation with the detent plate, oscillatory means adapted to alternately close and open a switch, means for oscillating the opening 60 and closing mechanism, a clock train for operating such means, and means adapted to normally engage and hold the train inactive and operated alternately by the detent

and dial plates to momentarily release the driving operating train.

5. A timing mechanism comprising a master clock train having a detent plate and a dial plate mounted in adjustable angular relation on the hour arbor of the train, means for alternately closing and opening 70 a switch, a clock train for operating the opening and closing means, and means for normally holding the driving train inert adapted to be momentarily released alternately from engagement therewith by the 75 detent and dial plates.

6. A timing mechanism comprising a master clock train having an hour arbor, a detent plate on the arbor, a dial plate in frictional angularly adjustable engagement with 80 the arbor and detent plate, oscillatory means for alternately closing and opening a switch, a clock train for oscillating the closing and opening means, and means normally holding the operating train inert, adapted to be momentarily released from the operating train by the detent plate for closing the switch and momentarily released from the operating 85 train by the dial plate to open the switch.

90 7. A timing mechanism comprising a master clock train having an hour arbor, a detent plate mounted on the arbor, a dial plate mounted thereon in adjustably angular relation to the detent plate, mechanism adapted when set in one position to close a switch and when set in another position to open a switch, means for setting and momentarily releasing such switch operating means alternately in both positions, a clock 100 train for operating such setting mechanism and detents for the operating clock train controlled by the detent and dial plates and alternately disengaged from the train thereby.

105 8. A timing mechanism comprising a master clock train having an hour arbor, a detent plate mounted on the arbor, a dial plate mounted thereon in adjustably angular relation to the detent plate, means adapted when 110 set in one position to close the switch and when set in another position to open the switch, a cam adapted to set the switch throwing mechanism alternately in its several positions and to release said mechanism 115 momentarily when operated, a clock train for operating the cam, and detent mechanism for the operating train adapted to be alternately released by the detent and dial plates and reset by the cam.

120 In testimony whereof I affix my signature in presence of two witnesses.

HERMAN C. NICHOLAUS.
